NOTCHING DEVICE

Theodore Loew, Brooklyn, N. Y., assignor to Trubenzing Process Corporation, New York, N. Y., a corporation of New York

Application September 28, 1949, Serial No. 118,320

11 Claims. (Cl. 223—2)

1

When garment parts or similar articles having a re-entrant angle are made by the familiar "run-and-turn" method, i. e. are first "run" or stitched together and then turned inside out, it is necessary to notch the fabric extending from the seam at the re-entrant point to the edge of the fabric so as to permit forming, as desired, either a smooth clean sharp corner or a well-rounded part at the "crotch" of the re-entrant angle.

This circumstance applies particularly to one-piece collars where the collartop portion meets the band-end.

This notching must be performed carefully; if it is too deep, it will cut the stitch or cause it to break out, and if it is too shallow, it will prevent forming a proper sharp or rounded crotch.

The object of this invention is to provide a simple machine which will perform the operation of notching quickly and accurately.

The invention will be understood by reference to the drawing, in which:

Fig. 1 is a diagrammatic section through a fabric part, e. g. a collar, comprising three layers of fabric stitched together near one edge;

Fig. 2 illustrates the fabric part shown in Figure 1 after it has been turned inside out;

Fig. 3 is a plan view of the end portion of a one-piece collar after the same has been run;

Fig. 4 is a plan view of the collar portion shown in Figure 3 after the same has been turned inside out;

Fig. 5 is an isometric view of a device for performing the notching operation; and

Fig. 6 is a side elevation, partly in section, of the notching device shown in Figure 5, showing how the notching operation is performed by the machine.

Referring to the drawings, Figure 1 shows a section of three plies of fabric 1a, 1b and 1c after they have been "run" or stitched together by a stitch 2, with the face-ply 1b in the middle and the lining ply 1c lowermost. After stitching, the plies are turned inside out, with the face-ply 1b uppermost, as shown in Figure 2.

Figure 3 shows one end portion of a one-piece collar when it is in a state corresponding to Figure 1, that is, after the plies have been run or stitched together by the stitch 2 but before the same has been turned inside out.

This one-piece collar comprises a collartop portion 3a and a band portion 3b. Where the collartop and band portions meet a crotch is formed, shown at 3c. It is at this point 3c that it is necessary to form the notch 4 so that when the collar

2

is turned inside out the crotch 3c will be smooth and nicely rounded.

The notch 4 must extend not quite to the stitch 2 but must come close enough to it—to within about $\frac{1}{2}$ " or thereabouts—so as to allow the formation of a smooth crotch at 3c after turning, as shown in Figure 4. The dotted line in this figure indicates the edge of the material turned in, in the neighborhood of the crotch, after turning.

10 To accomplish this notching, a template 5 is provided as shown in Figure 5. This template has a portion 5a corresponding to the end portion of a collartop of a one-piece collar and a portion 5b corresponding to the end portion of the collar band. Between them is a re-entrant part 5c. The stitch 2 shown in Figure 3 is intended to fit snugly against the edge of the template in the neighborhood of the re-entrant portion 5c. In this way the crotch of the collar is accurately located in the machine.

The template 5 is mounted on a swinging arm 6 which is pivoted at 7 to a base 8. The pivot 7 may be adjustable so as to allow free swinging of the arm 6 without shake.

25 Fastened to the base 8 is an upright rod 9 which carries on it a slideable block 10. Projecting laterally from the block 10 is a short rod 11 carrying another small block 12 which is held in position on the rod 11 by means of the set screw 13.

30 A pointed knife blade 14 is mounted on this block 12 by means of its shank 14a which is positioned on the block 12 by means of the pins 15. The screwhead 16 clamps the shank 14a against the face of the block 12 thereby securing the knife blade 14 firmly in predetermined position. A guard member 17 fastened by screws 18 to the block 12 completes the essential details of the machine.

40 In operation, after the part has been run, it is slipped over the template 5 as shown by the dotted lines in Figure 5 and in cross-section in Figure 6. The fabric part to be notched is firmly pressed on the template so that the stitching at the crotch 3c of the collar is pressed against the re-entrant part 5c of the template 5. The template is then swung towards and beyond the point of the knife blade 14 so that the point of the knife first pierces the fabric just above the

45 re-entrant part 5c and then, by continuing the motion of the arm, cuts the fabric from the piercing point out to the edge of the fabric so as to form notch 4.

50 A single rapid stroke of the arm 6 suffices to accomplish this result. The guard 17 minimizes

the danger of an operator making accidental contact with the knife blade 14.

It is necessary to adjust the position of the blade 14 so that its point will come substantially in the center of the re-entrant part 5c of the template and just above it by about $\frac{1}{32}$ " or slightly more. The vertical adjustment for this purpose may be obtained by sliding the block 10 up and down on the rod 9 until the desired height is obtained after which block 10 is locked in position by means of set screw 19.

Alternatively, the block 10 may be permanently fastened to the rod 9 and the vertical adjustment of the point of the knife 14 may be obtained by rocking the block 12 around the rod 11 so as to raise or lower the point of the knife 14 to the desired setting. Lateral adjustment of the knife is obtained by sliding the block 12 on the rod 11 to the desired position. In other words, both the lateral and the vertical adjustments may be obtained by rotating and sliding the block 12 on the rod 11. This is the preferred way of obtaining the necessary adjustment.

What I claim is:

1. In an apparatus for notching a run-and-turned fabric part after running but before turning, the combination of a stationary base; a pointed flat cutting member stationarily mounted on said base vertically spaced from the same; a supporting member adapted to hold and locate said fabric part by means of the running stitch in the neighborhood of the edge portion to be notched; and pivoting means turnably attaching said supporting member to said base so that said supporting member is turnable past said pointed flat cutting member about an axis being normal to the plane of said pointed flat cutting member, thus enabling turning of said supporting member with said fabric part held by the same towards said pointed flat cutting member so as to first cause the point of said pointed flat cutting member to pierce the fabric part close to the running stitch between said stitch and the edge portion to be notched and then to cause the cutting edge of said pointed flat cutting member to cut the fabric from said piercing point to said edge portion.

2. In an apparatus for notching a run-and-turned fabric part after running but before turning, the combination of a stationary base; a pointed flat cutting knife stationarily mounted on said base vertically spaced from the same; a template adapted to hold and locate said fabric part by means of the running stitch in the neighborhood of the edge portion to be notched; and pivoting means turnably attaching said template to said base so that said template is turnable past said pointed flat cutting knife about an axis being normal to the plane of said pointed flat cutting knife, thus enabling turning of said template with said fabric part held by the same towards said pointed flat cutting knife so as to first cause the point of said pointed flat cutting knife to pierce the fabric part close to the running stitch between said stitch and the edge portion to be notched and then to cause the cutting edge of said pointed flat cutting knife to cut the fabric from said piercing point to said edge portion.

3. In an apparatus for notching a run-and-turned fabric part after running but before turning, the combination of a stationary base; a pointed flat cutting knife stationarily mounted on said base vertically spaced from the same; a template adapted to hold and locate said fabric part

by means of the running stitch in the neighborhood of the edge portion to be notched; pivoting means turnably attaching said template to said base so that said template is turnable past said pointed flat cutting knife about an axis being normal to the plane of said pointed flat cutting knife, thus enabling turning of said template with said fabric part held by the same towards said pointed flat cutting knife so as to first cause the point of said pointed flat cutting knife to pierce the fabric part close to the running stitch between said stitch and the edge portion to be notched and then to cause the cutting edge of said pointed flat cutting knife to cut the fabric from said piercing point to said edge portion; and means for adjusting the position of said pointed flat cutting knife relative to said base by turning about an axis parallel to the axis of turning of said pivoting means and sliding in direction of said axis.

4. In an apparatus for notching a run-and-turned fabric part after running but before turning, the combination of a stationary base; a knife support on said base including a knife supporting rod; a pointed flat cutting knife mounted on said knife supporting rod slidably along and turnably about said rod and extending in a plane normal to said rod; means for locking said flat cutting knife to said knife supporting rod in any desired position of sliding and turning; a supporting member adapted to hold and locate the fabric part by means of the running stitch in the neighborhood of the edge portion to be notched; and pivoting means turnably attaching said supporting member to said base so that said supporting member is turnable past said pointed flat cutting knife about an axis being parallel to said knife supporting rod, thus enabling turning of said supporting member with said fabric part held by the same towards said pointed flat cutting knife so as to first cause the point of said pointed flat cutting knife to pierce the fabric part close to the running stitch between said stitch and the edge portion to be notched and then to cause the cutting edge of said pointed flat cutting knife to cut the fabric from said piercing point to said edge portion.

5. In an apparatus for notching a run-and-turned fabric part after running but before turning, the combination of a stationary base; a knife support on said base including a knife supporting rod; a pointed flat cutting knife mounted on said knife supporting rod slidably along and turnably about said rod and extending in a plane normal to said rod; means for locking said flat cutting knife to said knife supporting rod in any desired position of sliding and turning; a template adapted to hold and locate the fabric part by means of the running stitch in the neighborhood of the edge portion to be notched; a supporting arm holding said template; and pivoting means turnably attaching said supporting arm to said base so that said template is turnable past said pointed flat cutting knife about an axis being parallel to said knife supporting rod, thus enabling turning of said template with said fabric part held by the same towards said pointed flat cutting knife so as to first cause the point of said pointed flat cutting knife to pierce the fabric part close to the running stitch between said stitch and the edge portion to be notched and then to cause the cutting edge of said pointed flat cutting knife to cut the fabric from said piercing point to said edge portion.

6. In an apparatus for notching a run-and-

turned fabric part after running but before turning, the combination of a stationary base; a supporting post mounted on said base; a knife supporting rod mounted on said supporting post slidably along and turnably about the same; means for locking said knife supporting rod to said supporting post in any desired position of sliding and turning; a pointed flat cutting knife mounted on said knife supporting rod slidably along and turnably about said rod and extending in a plane normal to said rod; means for locking said flat cutting knife to said knife supporting rod in any desired position of sliding and turning; a supporting member adapted to hold and locate the fabric part by means of the running stitch in the neighborhood of the edge portion to be notched; and pivoting means turnably attaching said supporting member to said base so that said supporting member is turnable past said pointed flat cutting knife about an axis being parallel to said knife supporting rod, thus enabling turning of said supporting member with said fabric part held by the same towards said pointed flat cutting knife so as to first cause the point of said pointed flat cutting knife to pierce the fabric part close to the running stitch between said stitch and the edge portion to be notched and then to cause the cutting edge of said pointed flat cutting knife to cut the fabric from said piercing point to said edge portion.

7. In an apparatus for notching a run-and-turned fabric part after running but before turning, the combination of a stationary base; a supporting post mounted on said base; a knife supporting rod mounted on said supporting post slidably along and turnably about the same; means for locking said knife supporting rod to said supporting post in any desired position of sliding and turning; a pointed flat cutting knife mounted on said knife supporting rod slidably along and turnably about said rod and extending in a plane normal to said rod; means for locking said flat cutting knife to said knife supporting rod in any desired position of sliding and turning; a template adapted to hold and locate the fabric part by means of the running stitch in the neighborhood of the edge portion to be notched; a supporting arm holding said template; and pivoting means turnably attaching said supporting arm to said base so that said template is turnable past said pointed flat cutting knife about an axis being parallel to said knife supporting rod, thus enabling turning of said template with said fabric part held by the same towards said pointed flat cutting knife so as to first cause the point of said pointed flat cutting knife to pierce the fabric part close to the running stitch between said stitch and the edge portion to be notched and then to cause the cutting edge of said pointed flat cutting knife to cut the fabric from said piercing point to said edge portion.

8. In an apparatus for notching a run-and-turned fabric part after running but before turning, the combination of a stationary base; a knife support on said base including a knife supporting rod; a knife holder mounted on said knife supporting rod slidably along and turnably about said rod; means for locking said knife holder to said knife supporting rod in any desired position of sliding and turning; a pointed flat cutting knife movably mounted on said knife holder and extending in a plane normal to said rod; means for locking said cutting knife to said knife holder in any desired position; a supporting member

adapted to hold and locate the fabric part by means of the running stitch in the neighborhood of the edge portion to be notched; and pivoting means turnably attaching said supporting member to said base so that said supporting member is turnable past said pointed flat cutting knife about an axis being parallel to said knife supporting rod, thus enabling turning of said supporting member with said fabric part held by the same towards said pointed flat cutting knife so as to first cause the point of said pointed flat cutting knife to pierce the fabric part close to the running stitch between said stitch and the edge portion to be notched and then to cause the cutting edge of said pointed flat cutting knife to cut the fabric from said piercing point to said edge portion.

9. In an apparatus for notching a run-and-turned fabric part after running but before turning, the combination of a stationary base; a knife support on said base including a knife supporting rod; a knife holder mounted on said knife supporting rod slidably along and turnably about said rod; means for locking said knife holder to said knife supporting rod in any desired position of sliding and turning; a pointed flat cutting knife movably mounted on said knife holder and extending in a plane normal to said rod; means for locking said cutting knife to said knife holder in any desired position; a template adapted to hold and locate the fabric part by means of the running stitch in the neighborhood of the edge portion to be notched; a supporting arm holding said template; and pivoting means turnably attaching said supporting arm to said base so that said template is turnable past said pointed flat cutting knife about an axis being parallel to said knife supporting rod, thus enabling turning of said template with said fabric part held by the same towards said pointed flat cutting knife so as to first cause the point of said pointed flat cutting knife to pierce the fabric part close to the running stitch between said stitch and the edge portion to be notched and then to cause the cutting edge of said pointed flat cutting knife to cut the fabric from said piercing point to said edge portion.

10. In an apparatus for notching a run-and-turned fabric part after running but before turning, the combination of a stationary base; a supporting post mounted on said base; a knife supporting rod mounted on said supporting post slidably along and turnably about the same; means for locking said knife supporting rod to said supporting post in any desired position of sliding and turning; a knife holder mounted on said knife supporting rod slidably along and turnably about said rod; means for locking said knife holder to said knife supporting rod in any desired position of sliding and turning; a pointed flat cutting knife movably mounted on said knife holder and extending in a plane normal to said rod; means for locking said cutting knife to said knife holder in any desired position; a supporting member adapted to hold and locate the fabric part by means of the running stitch in the neighborhood of the edge portion to be notched; and pivoting means turnably attaching said supporting member to said base so that said supporting member is turnable past said pointed flat cutting knife about an axis being parallel to said knife supporting rod, thus enabling turning of said supporting member with said fabric part held by the same towards said pointed flat cutting knife so as to first cause the point of said

pointed flat cutting knife to pierce the fabric part close to the running stitch between said stitch and the edge portion to be notched and then to cause the cutting edge of said pointed flat cutting knife to cut the fabric from said piercing point to said edge portion.

11. In an apparatus for notching a run-and-turned fabric part after running but before turning; the combination of a stationary base; a supporting post mounted on said base; a knife supporting rod mounted on said supporting post slidably along and turnably about the same; means for locking said knife supporting rod to said supporting post in any desired position of sliding and turning; a knife holder mounted on said knife supporting rod slidably along and turnably about said rod; means for locking said knife holder to said knife supporting rod in any desired position of sliding and turning; a pointed flat cutting knife movably mounted on said knife holder and extending in a plane normal to said rod; means for locking said cutting knife to said knife holder in any desired position; a template adapted to hold and locate the fabric part by

means of the running stitch in the neighborhood of the edge portion to be notched; and pivoting means turnably attaching said template to said base so that said template is turnable past said pointed flat cutting knife about an axis being parallel to said knife supporting rod, thus enabling turning of said template with said fabric part held by the same towards said pointed flat cutting knife so as to first cause the point of said pointed flat cutting knife to pierce the fabric part close to the running stitch between said stitch and the edge portion to be notched and then to cause the cutting edge of said pointed flat cutting knife to cut the fabric from said piercing point to said edge portion.
